UNITED STATES PATENT OFFICE.

JULIUS ERLENWEIN, OF EDENKOBEN, GERMANY.

FILE-CUTTING MACHINE.

SPECIFICATION forming part of Letters Patent No. 447,149, dated February 24, 1891.

Application filed September 23, 1890. Serial No. 365,877. (No model.)

To all whom it may concern:

Be it known that I, JULIUS ERLENWEIN, manufacturer, of Edenkoben, in the Kingdom of Bavaria and German Empire, have 5 invented new and useful Improvements in File-Cutting Machines, of which the following is a specification, reference being had therein to the accompanying drawings.

This invention relates to the arrangement 10 and construction of a new or improved file-cutting machine, which consists of four main parts, viz: the device for holding the chisel or cutter, in combination with automatic feeding mechanism; the mechanism which 15 intensifies the blow struck upon the end of the file and raises the latter from its anvil; the screw-gear which operates the automatic cutting mechanism and causes the cuts to be wider in the center, and finally the table and 20 carriage which operate automatically and enable the serrations in the files to be cut at any desired angle.

This new or improved file-cutting machine 25 is illustrated in the accompanying drawings, in which—

Figure 1 is a side elevation of the machine. Fig. 2 is a front elevation of the same. Fig. 3 is a detail side elevation of the adjustable file-supporting table of the machine. Fig. 4 30 is a plan view of the same; and Figs. 5 to 9 are detail views of parts of the machine, hereinafter more particularly described.

b and c are two standards erected upon a pedestal a, Figs. 1 and 2, and carry between 35 them a chisel blade or cutter d. In the latter is arranged an anvil e, formed of a cylindrical block. The cutter enters the pedestal a by means of a screw-threaded pin or projection g'', and is fixed in the desired position by the nut f. The anvil e is formed upon 40 its periphery with a transverse groove h, which is enlarged toward the center and receives the end of a soft-zinc strip, which is subsequently laid over the periphery of the anvil e. The zinc strip is used to protect the 45 side of the file which is first cut or serrated from the blows in cutting the serrations formed on the other side, which is last cut. A table y is arranged higher up the standards 50 b and c upon bearings k i, and consists of two T-irons z, Figs. 3 and 4, connected to-

gether by cross-pieces m and l. On the right side and somewhat below the same is mounted a screw-spindle n, which rests upon the bearings r o, and is rotated by means of the 55 crank-handle p. The rotary motion of the spindle n is independent of that of the machine. On the opposite end there is mounted upon the spindle n a sleeve u, which can be easily moved to and fro. It is perforated 60 and can be easily displaced upon the end of the spindle. The latter is furnished near the bearing o with a pin v, acting as a carrier and engaging for this purpose with a notch v' of the lengthening piece u. Between the 65 bearing s and the disk t, fixed to the sleeve u, is arranged a spring w, which serves to couple the spindle and sleeve n and u together. Upon the screw-spindle n a nut B is mounted, being connected at its upper end with a carriage A, sliding upon the rails z. Upon the end of the spindle n is mounted a toothed wheel x and a loose lever y', together with two pawls 1 and 2, which engage with the teeth of the wheel x, so that the lever y' may, 70 when actuated, impart a rotary motion to the wheel x, the sleeve u, and the spindle n.

The lever y' is connected by means of a sliding piece movable in a slot of the lever, with a link 3, which can be adjusted by a 75 coupling-clamp 4. The rear end of this link 3 rests in a circular socket 13, connected with an adjustable nut 7. The latter moves upon a screw-threaded bolt 6, the end of which rests in a groove 14 of the disk 5. The latter 80 is fixed upon one end of a shaft 32, mounted in suitable bearings 40 and carrying at its other end a disk 33, which is furnished with a pin 34, engaging in an opening 35 of the connecting-rod 36. The latter is jointed with 85 a crank-lever 37, which embraces the pin 38 of the disk 39, keyed upon the driving-shaft V. At each revolution of the said driving-shaft V the disk 5 is rotated by means of the connecting-rod 36, the disk 33, and the shaft 90 32, and the connecting rod or link 3 causes the lever y' to oscillate, so that the pawls 1 and 2 will move one tooth of the wheel x. This causes the spindle or shaft n to rotate 95 and the carriage A to move with the file-holder 18, carried by the carriage A, toward the chisel or cutter.

The nut 7 above mentioned is actuated by imparting a suitable rotary motion to the screw-bolt 6; whereby the pawls 1 and 2 may be caused to move several teeth of the gear-wheel α , the consequence of this arrangement being that a sham stroke or cut may be made at times, while at other times a real cut is formed. A lever 8, connected by a socket-joint 15 to the front end of the connecting rod or link 3, extends upward through a guide 16 on the spindle n and terminates with a knob h^2 . When this lever 8 is drawn up or down, the oscillations of the lever y' will be long or short, and hence a different cut will be formed. Thus finer teeth or serrations can be made at the beginning and at the end of the file than in the center. This adjustment of the lever can be limited by stop-pins.

As soon as a file has been fully cut the lever g , fixed to the rail z of the table, is pulled, whereby the short sleeve u is released from the long screw-spindle, so that the return motion of the carriage A can now be accomplished by means of the crank-handle p . When the carriage A has been moved sufficiently far from the chisel or cutter, the spindle and sleeve n and u are again connected together by merely releasing the lever g from its last position, so that the spring w may now effect the coupling. The file-holder above mentioned is arranged upon the carriage A in such a manner that each file can be accurately set in a central position. This is effected by means of the two screws 11 and 12, Figs. 3 and 4, between which the front end is guided, while the rear and pointed end of the file can be suitably set.

A mechanical device C is fixed below to the connecting-piece m of the table y , serving to give the table a suitable angular position relatively to the chisel or cutter. This device C consists of a nut C' , resting in bearings 19 and through which moves a screw-spindle 20, set in rotation by a crank-handle 21, and fixed by its upper end to the connecting-piece m . The automatic motion of the chisel-holder and of the depressing device is illustrated in Figs. 5 to 7. A plate D, fixed to the standard c , is provided along its longitudinal sides with rails or bars E F, between which can slide a sledge G, furnished at its upper end with a screw-spindle H, imparting motion thereto. The latter turns in a nut J, provided on its periphery with teeth gearing with a worm K and rests in a fork-shaped bearing L, which prevents it from moving laterally. The worm K is carried in a bearing N of the plate D. Upon the prolongation of the axis of the worm is mounted a hand-wheel M, by turning which the nut J is rotated and the screw-spindle H, with the sledge G, is moved up and down. Upon a pin Q, fixed to the sledge G, the lever P is pivoted, which carries the chisel or cutter. The rear end of the lever P carries a hinge R', in which a rod R engages. The latter passes through a

frame S, provided with a spring T, and carries at its upper end two rings U, which clasp the driving-shaft V. Between the two rings U a projection or roller W is arranged to pivot upon a pin w' . The roller W is located in a small cavity or recess V' of the driving-shaft V, and hence when the said shaft V accomplishes one revolution the rod R is raised and the front end of the lever P, carrying the chisel or cutter, is pressed down upon the file. When, on the contrary, the roller W enters the recess V', the rod R sinks and the lever P is correspondingly raised at its outer end.

To intensify the pressure of the chisel, a spring T is arranged in the frame S, while another spring X is attached to an eye below the hinge R' and on one side of the lever P. This spring X can be more or less contracted or expanded by a set-screw Y and assists the raising of the chisel. The front end of the lever P carries an arm P', which is connected by means of a screw-bolt P'' to a rod a'. The latter is jointed to the block or chisel holder d' by means of a bayonet-joint a''. Two nuts b' b'' are screwed upon the rod a' and serve to further secure the bayonet-joint. The opposite end of the block d' carries a pressure-screw e', furnished with nuts f'. This screw e' operates against a plate g', behind which the chisel is arranged in a notch or recess d'' and firmly held by the plate g' and the pressure-screw e'. The sledge G carries a lever h, which pivots upon the pin i'. This lever is furnished at its rear end with a link m'' and a rod or bar k', which is provided for the purpose of adjustment with a coupling-clamp k'', and is connected by the links b'' and m' and lever b' with the axis x'' and the hammer a'', Fig. 2. The axis x'' is guided through brackets A', 29, and 30 of the standard c.

Upon the driving-shaft V is mounted a disk x', provided with a cam 27 and operating at each revolution upon the projection z', connected with the axis x''. A spiral spring o' is coiled upon the rod k' between the fixed ring o'' and the projection or bracket c'', fixed to the standard c and serving as a guide for the said rod k'. Another spring p' is arranged between the stop 31 and an adjustable ring 42 of the axis x'', and below the bracket A' of the standard c another spring p'' is coiled on the axis x''. One end of the spring p'' bears against the ring l'', adjustable on the axis x'', while its other end bears against a disk f'', sliding in the standard c and capable of being displaced by a screw-spindle i'', carried by the bracket A', with the aid of a crank-handle e'', so that the spring p'' may be more or less contracted or expanded.

The arm h' of the lever, Figs. 5 and 6, is bent down and provided with a hollow boss or enlargement. In the latter is arranged a rod r', acting upon the file and held in the said boss or enlargement by the screw s'. Said arm h' can be adjusted by means of a

5 screw-spindle c' , which is guided by the nut v' of a flange u' , each integral with the sledge G , and by the nut w'' appertaining to the arm h' . The nut v' moves upon a pin v'' . For this purpose the head of the spindle c' is perforated, so that the lever h' can be made to assume any suitable position.

10 The above-described machine operates in the following manner: When the driving-pulley B'' , mounted on the shaft V , rotates in the direction of the arrow shown in Fig. 1, it imparts a similar motion to the disk x' and raises, with the aid of the cam 27, the projection or tappet z' , and with it the axis x'' 15 and the hammer a'' , fixed thereon. The lifting of the axis x'' causes the rod k' to sink, the arm h' pressing the file upon the anvil by means of its rod r' . The springs p' and p'' of the axis x'' , which are thus contracted, 20 act upon the latter and cause the hammer to deliver a downward blow as soon as the disk x' has released, owing to its inclined plane 28, the projection z' of the axis x'' . This blow can be increased, if required, by turning 25 the spindle i'' by means of the hand-wheel e'' and hence by tightening the spring p'' . When the blow has been struck, the curvature of the cam 27 comes again in contact with the projection z' to raise the hammer. 30 At this moment the roller W enters the recess V' of the driving-shaft V , and the spring T , in connection with the spring X , raises the front part of the lever P , carrying the chisel or cutter, and hence withdraws the said cutter or chisel from the file. At the same time 35 the connecting-rod 36 is raised by the pin 38 of the disk 39, mounted on the driving-shaft V , so that the disks 5 and 33 accomplish a revolution and impart a motion to the toothed 40 wheel x through the connecting-rod or link 3, the lever y' , and the pawls 1 and 2, the said wheel x moving the carriage A and the file fixed thereon forward again by means of the spindle n . As soon as this is over the operation 45 is repeated, the chisel or cutter being placed again over the file by reason of the roller W having again left the recess V' , and by means of such roller the rod R and the spring T are actuated, whereupon the hammer 50 delivers the next blow. When the file has been cut over about a quarter of its length, the attendant pulls the knob h^2 . The serrations or cuts will now become a little coarser, but very slightly so. When the file is three-quarters cut, the knob h^2 is pushed back and the serrations become immediately finer. The above-described machine can cut all kinds 55 of files and by it old files may be readily re-cut when dulled.

60 What I claim, and desire to secure by Letters Patent of the United States, is—

1. In file-cutting machines, the mechanism for automatically feeding the file, indicated by a screw-spindle n , connected with the file-table and rotated by the toothed wheel x , the rotation of which wheel is carried out by pawls with the aid of a lever y' , a connect-

ing-rod 3, jointed to the link 36 by means of the socket-joint 13, the nut 7, the shaft 32, and the disks 5 and 33, and a crank-lever 70 75 37, actuated by the driving-shaft for the purpose of regulating the extent of the stroke of the pawls and of obtaining coarse or fine cuts or serrations, substantially in the manner and for the purposes hereinbefore described. 75

2. In a file-cutting machine, the mechanism for moving the chisel or cutter holder automatically, indicated by the arrangement of an adjustable pin Q , upon which the lever P , carrying the chisel, is arranged to pivot, the 80 other end of the said lever—*i. e.*, the end opposite that carrying the chisel—being connected by a rod R with two rings U , carrying a roller W , and clasping the driving-shaft, while the said roller enters, when the 85 driving-shaft rotates, a recess formed in the said shaft, so that the up-and-down motion thereby imparted to the lever carrying the chisel or cutter can be intensified by the springs T X , substantially as described. 90

3. In a file-cutting machine, the mechanism for pressing the file tightly upon the anvil and for actuating the hammer, indicated by a movable and adjustable lever h' , one end of which is connected with a pressure-piece 95 r' , while its other end is jointed by means of a rod k' and a lever b' with the axis x'' , carrying the hammer, which axis is surrounded by springs and is furnished with a projection z' , actuated by the cam x' , mounted on 100 the main shaft, substantially in the manner and for the purposes hereinbefore described.

4. In a file-cutting machine, the combination, with a table having a threaded spindle journaled thereunder, provided at its ends, 105 respectively, with a handle and a ratchet-wheel, and a nut movable on the spindle and carrying at its upper end a carriage movable on the table, of a lever pivoted on the spindle and carrying pawls engaging the ratchet-wheel, a shaft journaled below the table and provided with a disk at each end, a lever-and-link connection between one of said disks and the pawl-carrying lever, and a lever-and-crank connection between the other of said 110 disks and a disk on the driving-shaft of the machine, substantially as shown and described, for the purpose set forth. 115

5. In a file-cutting machine, the combination, with a vertically-guided sledge and a lever pivoted on the sledge and carrying a chisel or cutter at its outer end, of a spring-controlled vertical lever connected at one end to the inner end of the chisel-carrying lever and having at its other end rings embracing 120 the driving-shaft of the machine, and a roller pivoted between the rings and entering a recess in the driving-shaft, substantially as shown and described. 125

6. In a file-cutting machine, the combination, with a vertically-guided sledge and a lever pivoted on the sledge and carrying a chisel or cutter at its outer end, of a lever pivoted to the sledge below the chisel-carry-

ing lever and provided at its outer end with a removable pressure rod or finger, a spring-controlled vertical axis mounted in bearings on the machine, carrying a hammer at its 5 lower end and having a projection or tappet on one side, lever-and-link connections between the axis and the chisel-carrying lever, and a cam-disk mounted on the driving-shaft of the machine and adapted to engage the

projection on the hammer-axis, substantially 10 as shown and described.

In witness whereof I have hereunto set my hand in presence of two witnesses.

Berlin, May 28, 1890.

JULIUS ERLENWEIN.
